(57) **CLAIM**

The ornamental design for a battery swapping station, as shown and described.

DESCRIPTION

FIG. 1 is a first perspective view of a first embodiment of the design;

FIG. 2 is a second perspective view of the first embodiment of the design;

FIG. 3 is a third perspective view of the first embodiment of the design;

FIG. 4 is a fourth perspective view of the first embodiment of the design;

FIG. 5 is a front view of the first embodiment of the design;

FIG. 6 is a rear view of the first embodiment of the design;

FIG. 7 is a left side view of the first embodiment of the design;

FIG. 8 is a right side view of the first embodiment of the design;

FIG. 9 is a top view of the first embodiment of the design;

FIG. 10 is a first perspective view of a second embodiment of the design;

FIG. 11 is a second perspective view of the second embodiment of the design;

FIG. 12 is a third perspective view of the second embodiment of the design;

FIG. 13 is a fourth perspective view of the second embodiment of the design;

FIG. 14 is a front view of the second embodiment of the design;

FIG. 15 is a rear view of the second embodiment of the design;

FIG. 16 is a left side view of the second embodiment of the design;

(Continued)

FIG. 17 is a right side view of the second embodiment of the design;
 FIG. 18 is a top view of the second embodiment of the design;
 FIG. 19 is a first perspective view of a third embodiment of the design;
 FIG. 20 is a second perspective view of the third embodiment of the design;
 FIG. 21 is a third perspective view of the third embodiment of the design;
 FIG. 22 is a fourth perspective view of the third embodiment of the design;
 FIG. 23 is a front view of the third embodiment of the design;
 FIG. 24 is a rear view of the third embodiment of the design;
 FIG. 25 is a left side view of the third embodiment of the design;
 FIG. 26 is a right side view of the third embodiment of the design; and,
 FIG. 27 is a top view of the third embodiment of the design.
